UNITED STATES PATENT OFFICE.

CARL PLASKET, OF FARIBAULT, MINNESOTA.

BATTERY-STEAMER.

1,325,861.

Specification of Letters Patent. Patented Dec. 23, 1919.

Application filed April 16, 1919. Serial No. 290,624.

To all whom it may concern:

Be it known that I, CARL PLASKET, a citizen of the United States, residing at Faribault, in the county of Rice and State of Minnesota, have invented certain new and useful Improvements in Battery-Steamers, of which the following is a specification.

This invention relates to certain new and useful improvements in method of and means for steaming storage batteries for the purpose of loosening the seal of paraffin, asphaltum, or whatever substance may be used for this purpose.

Heretofore, so far as I know, it has been the practice to remove this covering or seal by means of hot knives, which is a tedious and slow way to accomplish the result. I propose to get the same result in a much cheaper, easier and quicker way.

It has been found that high pressures are injurious to the batteries as well as being dangerous, requiring constant attention on the part of the operator and also requiring greater heat than I find to be necessary or desirable.

I have found by experiments that slow steady heating at a very low pressure, never exceeding a pressure of five pounds, and softening the paraffin, etc., slowly brings about the best results and avoids all possible liability of injury to the batteries.

I provide simple means for steaming the material to be softened and loosened and at the same time make provision for simultaneously warming covers and jars that are often warped out of shape, before assembling the battery.

I provide a steamer that can be readily employed in connection with a gas or other heater and readily removed from place to place as may be desired.

Other objects and advantages of the invention will hereinafter appear, and the novel features thereof will be specifically defined by the appended claims.

The invention, in its preferred form, is clearly illustrated in the accompanying drawings, which, with the numerals of reference marked thereon, form a part of this specification, and in which—

Figure 1 is an elevation of my improved steamer.

Fig. 2 is a substantially central vertical section through the same as on the line 2—2 of Fig. 3.

Fig. 3 is a view, showing the steamer in

cross section, and its application to a storage battery, the latter being shown in top plan, with the covering sheet partly removed.

Like numerals indicate like parts throughout the several views.

Referring to the drawings:

1 designates the container or receptacle, made preferably of galvanized iron, watertight, and of any desired shape and capacity. It is designed to be placed over a gas, gasoline, or other heater, or upon a gas plate, and to contain water, say up to the line *w—w*, see Fig. 2.

The top, which is made steam-tight, is provided with a suitable filling opening closed by a steam-tight closure 2.

The upper portion of the container is provided with a partition 3, having perforations 4, communicating with the compartment 5, which forms a steam-separating chamber which extends the entire width of the container as shown and from which lead small pipes or nozzles 6 to receive the ends 7 of flexible tubes 7, each nozzle being provided with a shut-off valve 8, all as seen best in Fig. 2.

From the bottom of the steam-separating chamber there extends a drip pipe 9, by means of which the water of condensation will drip into the bottom of the compartment of the container as will be understood upon reference to Fig. 2. The vent drip is so constructed that the steam will not interfere with the water dripping from the steam-separating chamber.

Within the container 1 I arrange an oven within which the covers and jars that have been warped or gotten out of shape can be warmed before reassembling the battery. This is clearly shown in Fig. 2. This chamber or oven 10 is disposed substantially centrally of the container as to height, but extends about two thirds of the distance from front to rear. It is supported from the walls of the container in any suitable manner and is provided with a shelf 11 of strong wire or similar material as shown and supported upon suitable supports 12, as seen clearly in Fig. 2.

A suitable door 13 is provided to give access to the interior of the oven, as seen in Figs. 1 and 2.

By positioning the oven substantially as shown it is in the path of the steam rising from the water in the bottom of the con-

tainer, and becomes readily heated, so that the articles placed in the oven may be readily and quickly heated to the required extent.

5 With the parts constructed and arranged substantially as above described the operation will be apparent, and, briefly stated, is substantially as follows;—

The steamer is placed over the source of heat, and the battery placed adjacent thereto, as seen in Fig. 3. As many tubes 7 as there are battery cells to be removed are inserted in place in the battery as seen in Fig. 3, in this instance three, the valves 15 8 of these tubes opened, and those of the others closed as shown in said Fig. 3, and the top of the battery covered with a piece of cloth or the like 14, to prevent the escape of the steam, as will be readily understood, 20 and in about ten minutes, more or less, the paraffin will be found sufficiently softened so that the cell can be readily removed.

During the interim the articles that have been placed in the oven are sufficiently 25 warmed by the steam rising from the water in the bottom of the container rising against the bottom of the oven and passing all around the said oven.

Each tube being provided with a shut-off 30 valve, I can use either three tubes for six volt batteries or all six tubes for twelve volt batteries.

The simplicity of the device and its 35 adaptation to different styles of batteries, and the readiness of application, as well

as its efficiency makes it a great time saver, besides requiring no skilled labor to accomplish the desired result.

Modifications in details of construction, arrangement of parts, etc., may be resorted to without departing from the spirit of the invention or sacrificing any of its advantages.

What is claimed as new is;—

1. A battery steamer comprising a container, a steam separator, an oven in the container, and a pipe connected with the steam separator for conveying steam therefrom to a battery. 45

2. A battery steamer comprising a container, a steam separator, an oven in the container, a pipe connected with the steam separator for conveying steam therefrom to a battery, and means for covering the battery to confine the steam. 50

3. A battery steamer comprising a container, a steam separator, an oven in the container, and a pipe connected with the steam separator for conveying steam therefrom to a battery, and a drip pipe from the 55 bottom of said steam separator leading to the bottom part of the container.

4. The method of loosening the seal on a storage battery, which consists in applying low-pressure steam thereto and covering the top of the battery to confine the steam, whereby the seal is gradually softened. 60 65

In testimony whereof I affix my signature.
CARL PLASKET.
